UNITED STATES PATENT OFFICE.

EDWARD H. JOHNSTON, OF PHILADELPHIA, PENNSYLVANIA.

VENTILATOR FOR CARS.

SPECIFICATION forming part of Letters Patent No. 651,627, dated June 12, 1900.

Application filed November 10, 1899. Serial No. 736,461. (No model.)

To all whom it may concern:

Be it known that I, EDWARD H. JOHNSTON, a citizen of the United States, residing in the city and county of Philadelphia, State of Pennsylvania, have invented a new and useful Improvement in Ventilators for Cars, &c., which improvement is fully set forth in the following specification and accompanying drawings.

10 My invention consists of a ventilator for a car or other vehicle composed of a fan, a wheel operating the same, a chest into which wind is admitted and by which it is directed to said wheel, means for controlling the running of the fan, and ball-bearings for the fan-shaft, whereby the latter rotates with ease and smoothness, said ball-bearing being seated in the collar or sleeve in which the shaft of said fan and wheel is mounted on rings, 15 which are fitted in said collar and retained by nuts or appliances on said shaft.

Figure 1 represents a partial side elevation and partial vertical section of a ventilator embodying my invention. Fig. 2 represents an irregular horizontal section on line $x\ x$, Fig. 1. Fig. 3 represents a perspective view of a detached portion. Figs. 4 and 5 represent horizontal and vertical sections, enlarged, respectively, on lines $x\ x$ and $y\ y$, Fig. 1.

20 Similar letters of reference indicate corresponding parts in the figures.

Referring to the drawings, A designates a case or chest which is supported on a suitable portion of the roof of a car or other vehicle and formed with chutes B B, which project in opposite directions and are open to the atmosphere, so as to admit a current of air into and through the chest.

C designates a wind-wheel which is located 25 within the chest A and secured to the shaft D, which passes vertically through the collar E and carries at its lower end the blades F of a fan, said collar depending from the plate G, which is secured below the chest A, in the present case to the roof of the car, and provided with balls H, which are seated between the inner ends of rings J and shoulders on the interior of the collar opposite to said rings, the latter entering the upper and lower ends 30 of said collar and being controlled and adjusted by the nuts or washers K on said shaft D, respectively above and below said collar,

thus providing ball-bearings for said shaft, so that the latter runs with ease and smoothness in the collar.

55

The chest A is provided with doors or valves L, the upper and lower ends of which are fitted in ways M in the upper and lower portions of the sides of said chest and so arranged that they may cover or uncover the openings N in said chest at the inner terminals of the chutes B, by which provision the volume of air admitted into said chest may be adjusted to full or partial extent or be entirely cut off from the same. Owing to the ways M, rain, dust, &c., 60 are prevented from beating through the chest at the upper and lower ends of the doors L. It will also be noticed that the pinions W, as well as the racks V, are inclosed in said ways M, and thus guarded from rain, snow, or dust, 65 &c., while the upper and low ends of the valves are also inclosed in said ways and similarly guarded.

Connected with the collar E is the hanger P, on which is mounted the lever Q, one end 70 of which is connected with the rod R and the other end provided with the shoe S, which is adapted to engage with the friction-pulley T, the latter being secured to the shaft D below the collar E. The rod R is passed through 75 the sleeve U, which is secured to the body of the car and provided with a hand wheel or lever whereby the rod may be operated to raise or lower the lever Q, and consequently cause the shoe to disengage the friction-pulley, 80 thus releasing the shaft and permitting the rotation or operation of the fan or to engage therewith, thus acting as a brake to stop or control said shaft and prevent the rotation and operation of the fan.

90 In order to move the valves or doors L, the same are provided with circular racks V, with which engage the pinions W, which are connected with the shaft X, the latter being suitably mounted on the body of the car and provided with a handle for rotating purposes, whereby the valves may be moved in opposite directions, so as to close or open the chutes B, and thus adjust the volume of air desired to be admitted into the chest to operate the 95 wind-wheel C, or the air may be entirely cut off, thus stopping said wheel, it being also evident that the rotation of the shaft D may be quickly and immediately prevented by the 100

engagement of the shoe with the friction-pulley, the same also being adapted to adjust the rapidity of rotation of said shaft by the extent of friction occasioned by the shoe on said 5 pulley. It will now be seen that when the car is in motion and the parts are in operative position the fan will be rotated, thus agitating the air in the car, whereby the latter will be cooled and ventilated and the foul air 10 displaced.

15 The chutes are disposed opposite to each other, and they extend tangentially from the chest A, whereby the fan will rotate in the same direction regardless of the direction of motion of the car.

20 In order to conveniently operate the lever Q, the lower portion of the rod R is held within the sleeve U by means of the collars or washers Y above and below the same, forming somewhat of a swivel, so that said rod may be rotated without being raised and lowered. The upper end of said rod is screw-threaded and fitted in a threaded opening in the block Z, on which the adjacent end of the lever Q 25 is mounted by the journals or pivots Z', it being evident that by operating the rod R the block Z may have up or down motions imparted to it, the same being imparted to said lever, the effect of which on the shoe S being 30 evident, while the rod retains either of its positions without the requirement of fastening devices.

Having thus described my invention, what I claim as new, and desire to secure by Letters 35 Patent, is—

1. A shaft, a wind-wheel and a fan respectively on opposite ends of said shaft, in com-

bination with a vertically-arranged collar with shouldered recesses in the upper and lower ends thereof, rings entering said recesses and seated against said collar, and balls interposed between said rings and collar, said shaft being mounted in said collar and rings, a supporting device for said collar, and nuts on said shaft at the opposite ends of said collar, bearing directly against said rings. 40 45

2. In a ventilator of the character stated, the combination with the wind-chest thereof, and an inlet thereon, of a valve for said inlet mounted on the wind-chest, a rack on said valve, a pinion meshing with said rack, a shaft carrying said pinion, a bearing for said shaft, and ways on said chest freely receiving and guarding the upper and lower ends of said valve, said pinion, rack and the upper 50 and lower ends of said valve being inclosed in said ways respectively.

3. A wind-chest, a wind-wheel therein, a fan, a rotary shaft, the latter carrying said wheel and fan, and a friction-pulley on said 55 shaft, in combination with a lever, a brake-shoe on one end of said lever, the same being adapted to engage said pulley, a bearing for said lever, a rising-and-falling block with a threaded opening, the other end of said lever being pivotally connected with said block, an operating-rod, and a sleeve in which said rod is swiveled, a portion of said rod being screw-threaded and engaging the thread of the opening of said block.

EDWARD H. JOHNSTON.
